TRAFFIC SIGNAL

Theodore E. Steiber, Bridgeport, Conn., assignor
of one-half to Arthur A. Johnson, Bridgeport,
Conn.

Application June 22, 1937, Serial No. 149,574

12 Claims. (Cl. 177—337)

This invention relates to a signal device and more particularly to the type of device for controlling traffic.

In current systems of operating traffic lights, a yellow caution signal is displayed to indicate a change of light from "stop" to "go," or "go" to "stop." This signal does not indicate how soon or how much time is left for the go or stop signal to remain lighted. A driver approaching the intersection has no means of telling whether the caution signal has been displayed for only a short time or whether its period of operation is about terminated, and does not know whether he can proceed through the signal or whether he should stop.

According to the present invention, a signal is provided in which the stop and the go lights are operated in the predetermined manner so as to indicate to a driver approaching the intersection that the lights are changing and approximately the amount of change that has taken place.

Preferably, according to the present invention, a plurality of lights are used to illuminate each signal. All of these lights are lighted during the period in which the stop or go signal is displayed. During the interval when it is desired to change the lights the individual lights in at least one of the signals will be extinguished seriatim. This indicates to the operator of an automobile approaching the intersection that a certain portion of the changing time has elapsed and gives him a fairly accurate idea when the other signal will be displayed and become controlling.

According to the present invention, the go signal on one side of the frame, for example north and south, is connected to the stop signal on the east and west and vice versa. The circuits for these signals are controlled by a means which will be operated only during the period in which a change in signal is to be made and which will cause the lights to extinguish seriatim in one set of signals and at the end of the seriatim operation cause all of the light sources in the other set of signals to be immediately flashed on.

It will be obvious that this operation will tend to decrease the number of traffic accidents which occur due to the operator failing to know that the caution light has been displayed for a long period and that the signal is about to change.

Care must be taken in using this mode of operation that the controlling means must function accurately for each operation. Accordingly, an electro-magnetically operated latch may engage

the contact drum controlling the operation of the lights or some portion of its drive and prevent the drum from overrunning so that the period of operation is always uniform and regular.

5. Further features and advantages will be apparent from the following specification taken in connection with the drawings.

In the drawings:

Figure 1 shows a perspective view of the traffic signal.

Fig. 2 shows a diagrammatic view of the traffic signal lights and the controlling circuit therefor.

Fig. 3 shows a vertical section of the traffic light.

15. Fig. 4 shows a detailed view of the controlling mechanism with the latch omitted.

Fig. 5a shows a developed plan view of the surface of the contact drum showing the positions of the contacts thereon.

20. Fig. 5b is a developed plan view of the surface of a modification of the contact drum for use with signal lamps adapted to be connected in parallel.

The traffic light according to the present invention is shown as embodying one for use with a two-way intersection. It is obvious that the light may be designed for any number of intersections.

The preferred form of the traffic signal herein disclosed comprises a housing 10 adapted to be suspended or supported in any desired manner. The housing 10 has a generally horizontally extending portion 11. Secured to the underside of portion 11 and depending therefrom is a vertically extending portion 12 of narrower dimensions, as shown in Fig. 3. The upper portion 11 of the housing is provided with horizontally disposed apertures 13 one for each approaching lane of traffic. The lower portion 12 of the housing

35. 40. 45. has a plurality of vertically disposed apertures 14 one for each approaching lane of traffic. A stop signal 15 for controlling traffic, for example in an east-west direction, is mounted in the housing and comprises three light sources or signalling units 15a, 15b and 15c, as shown in Fig. 2. A stop signal 16 also mounted in the upper portion 11 for controlling traffic in the north-south direction and comprises three light sources or signalling units 16a, 16b and 16c.

50. The light sources herein disclosed are preferably luminous gaseous discharge tubes although other signalling means may be used in order to obtain the desired result. These tubes are constructed so as to be generally U-shaped, the legs 55 of the U being positioned behind the opposite

apertures in the walls of the upper portion 11 and the section of the tubes between the legs of the U being made with a slight transverse bend, as shown in Fig. 3, so that all of the tubes may be positioned in the casing with the legs or signalling portions disposed in the same general horizontal plane behind the apertures. These tubes are mounted in the casing on a plurality of supports 17 which extend behind the operative legs of the tubes and hold them in a position to be displayed or to illuminate the signalling aperture. The supports 17 have an extension 18 projected up in back of the tubes to shield the same from lighting up apertures opening in the opposite direction. These surfaces 18 are finished so as to produce a light-reflecting surface for the tubes. In each corner of the frame, as shown in Fig. 2, a partition 19 is provided connecting the supports and shielding members to the frame to prevent the light from giving a false signal to traffic coming in the opposite direction. The portion of the tubes extending between the operative legs of the U may be rendered opaque by coating them with suitable material to also prevent them from giving a false signal.

The depending portion 12 of the housing 10 contains a signal 20 for controlling the east-west traffic and comprising tubes or signalling units 20a, 20b and 20c. A signal 21 is also provided in housing portion 12 for controlling traffic in the north-south direction and comprises tubes or signalling units 21a, 21b and 21c. These tubes are preferably luminous gaseous discharge tubes although any suitable signalling means may be used in place thereof. These tubes are formed in the shape of a U and are nested one within the other as shown in Figs. 2 and 3. The legs of the U, as shown in Fig. 2, are positioned behind the opposite apertures in the housing 12 and are shielded from one another by a plurality of shields 22 which prevent the giving of false signals and which also form reflecting surfaces for the tubes.

Mounted in the upper portion of the housing 11 is a supporting frame 23 upon which is secured a plate 24. The plate extends over the area of the upper section and provides an adequate mounting for the necessary mechanism for energizing and controlling the lights. A transformer 25 for energizing the luminous gaseous discharge tubes is mounted on the plate so as to be carried by the unit. The mechanism for controlling the various tubes so as to give the desired signals as will be more fully explained is also mounted on this plate. A dome 40 is secured to the top of the housing so as to overlie the top of the upper portion and is projected upwardly to provide ample space for the transformer and control unit for the light. In an upwardly projecting portion at the center of the dome is an insulating bushing 41 of rubber or similar insulating material which will make a water-tight bushing through which a pair of leads 42 for the transformer and a pair of leads 43 for the motor are carried. These leads are the only ones which need be connected to the traffic light. The leads from the motor go to the usual control box 55 containing mechanism comprising a switch for closing the circuit to the motor whenever it is desired to change signals and to display a caution signal during the interval between the change to warn approaching drivers that the signal is about to change.

According to the present invention, the lights in the signals are so operated as to indicate

to the driver approaching the intersection the interval of time in general that has elapsed since the caution signal has been initiated so that he may determine whether or not he should proceed or stop.

In the preferred form of the present invention, the stop lights facing traffic in one direction are connected to operate with the go lights in the other direction and vice versa so that these signals will operate together.

The desired control for the lights may take various forms such as relay systems and the like, but according to the present invention it is achieved by employing a drum 38 having stepped contact surfaces 39 thereon. This drum is mounted on a shaft 37 supported by a supporting bracket 27 mounted on plate 24 and is driven from a motor 26, also mounted on plate 24. The motor has a worm 31 secured to its shaft and cooperates with a worm gear 30 on a shaft 29 supported in a pair of bearings 28 of the supporting bracket 27. The shaft 29 has secured thereto a friction plate 32. Mounted to slide on the shaft 29 is a sleeve carrying a plate 33 having a friction face 34. The plate 33 is spring pressed so that its friction face cooperates with the plate 32 to form a slip connection between the motor and the drum. The sleeve has mounted thereon and rotating therewith a worm 35 meshing with a worm gear 36 on the shaft 37 which carries the contact drum. As shown in the present invention, the drum will turn 180° during one change of lights. This however is optional and may be varied to suit varying conditions, for example the drum may make one revolution to accomplish the same result by having contacts extend around the entire surface.

An insulating block 44 is carried by the supporting bracket 27. A contactor is mounted on the block and extends into cooperative relation with the drum to control one set of lights. This contactor comprises three insulated contacts 45a, 45b and 45c which engage the drum at the under surface thereof. A second insulating block 46 is carried by the supporting bracket and has mounted thereon a contactor comprising insulated contact elements 47a, 47b and 47c which engage the upperside of the drum 180° from contacts 45a, 45b and 45c and control the other set of lights.

As shown in Fig. 2 the pairs of tubes 20a, and 21a, 20b and 21b, and 20c and 21c are connected at one end respectively to one side of each of the three secondary windings of the transformer and the said tubes are connected at their other ends in the following manner. The three horizontal red east-west tubes 15a, 15b and 15c are connected in series with the vertical green north-south tubes 21a, 21b and 21c, and the three horizontal north-south red tubes 16a, 16b and 16c are connected with the three vertical green east-west tubes 20a, 20b and 20c. It will be seen, therefore, that when connected in this manner the stop light on one side of the frame or housing operates with the go light on the opposite side of the frame. The tubes are connected to the contacts which when engaging the contact portions 39 of the control drum in such a manner so as to close the circuits to the tubes, the contact 45a is connected to and controls the tubes 15a and 21a so that they operate at the same time. Contact 45a is connected to the tubes 15b and 21b and contact 45c is connected to 15c and 21c so that each pair operate together. Similarly contact 47a is connected to tubes 16a and 20a. Contact

47b is connected to tubes 16b and 21b and 47c is connected to tubes 16c and 21c. From the above connections, it will be seen that when the separate contacts close the circuit to the transformer through contacts 39 the pairs of tubes connected thereto will be energized.

A developed plan view of the drum for controlling the lights according to the present invention is shown in Fig. 5a. The contact surfaces formed on the drum extend through 180° so that one half of a revolution of the drum will complete a change of lights. The contact surface is formed with a short section 39a which will engage the contact brushes 45a and 47a for approximately 60° of rotation of the drum. Contact 39b extends further and will engage contacts 45b and 47b for a period of about 120° of rotation of the drum. Contact 39c extends for slightly less than 180° of the drum to insure that the lights are extinguished before the other set flashes on. This contact engages contacts 45c and 47c for approximately the full length of time required in changing the signal. Contacts 39x, integral respectively with contacts 39a, b, and c, extend around the entire circumference of the drum and engage contacts 54 which connect the contacts on the drum respectively to one side of each of the secondary transformer windings. It will be seen that when the drum is in the position shown in Fig. 2, a circuit will be closed through all of the light sources in signals 15 and 21. When it is desired to change the signal from go to stop, or stop to go, the controller in the usual control box 55 is operated to close the circuit to the motor which causes the drum to rotate in the direction of the arrow, Fig. 2. As the drum rotates, contact 45a will leave the contact surface after 60° of rotation of the drum and will cause signal lights 15a and 21a to be extinguished. Continued rotation of the drum for another distance of 60° will cause contact 45b to leave the contact surface and will cause the lights 15b and 21b to become extinguished. Further rotation of the drum for another 60° will cause the contact 45c to leave the contact surface and extinguish the lights 15c and 21c. As the drum continues to move, the contact surface will immediately engage all of the contacts 47 to cause all of the lights associated therewith to be energized. The mode of operation may be summed up as follows: When it is desired to change the traffic signal from stop to go, or go to stop, the lights being displayed in the various directions will be caused to be extinguished seriatim and immediately upon extinguishing the last light of one signal, for example the go signal, the entire stop signal on that signalling side flashes on. This operation gives an oncoming motorist an indication of the amount of time elapsed from the beginning of the caution period so that he can decide instantaneously whether to stop or whether he can pass the light before the signal changes completely.

Fig. 5b shows a developed plan view of a drum 38' having a modified arrangement of stepped contacts thereon, adapted to replace drum 38 providing that the luminous gaseous discharge tubes are replaced by light sources adapted to be energized in parallel, such as, for instance, incandescent lamps.

When this is the case, the multiple secondary transformer 25 may be omitted, one power lead 42 being connected to the contact 54' while the other power lead 42 is connected to one terminal

of each of the vertically disposed light sources 28a, b, and c, and 21a, b, and c. Connections from contacts 45a', b', and c' and contacts 47a', b', and c' to light sources 15 and 16 are the same as those shown in Fig. 2 between the said light sources and contacts 45a, b, and c, and 47a, b, and c.

Contact surfaces 39a', b', c', and x' are spaced respectively to extend over about 60°, about 120°, slightly less than 180°, and 360° of the circumference of drum 38' in the same manner as contact surfaces 39a, b, c, and x of drum 38.

Operation of the signal by rotation of drum 38' is the same as in the case of drum 38 in Fig. 5a.

With the caution signal of the type disclosed in the present invention, care must be taken to prevent the drum from overrunning since such an occurrence would cause the caution signal to be inefficient for the purpose designed, namely, to give an indication of the elapsed time of the caution period. Accordingly, means have been provided for preventing such an occurrence. A pair of pins 48 are positioned on the worm gear 36, 120° apart and in definite spaced relation with respect to the contact surfaces 39. A lever 50 is pivoted intermediate its ends to the supporting bracket 27 to a pivot 51. One end of the lever has a hook portion adapted to engage the pins on the gear and prevent the gear from further rotation. The other end of the lever is weighted to cause the lever to normally move into hook-engaging position. The latter end of the lever is connected to a core 53 operating in a solenoid 49. The solenoid is connected in series in the motor circuit so that when the circuit is closed to the motor by the control switch 55, the initial surge of current will be sufficient to raise the core and to release the hook from the pin and, as the motor starts to rotate and move the drum and the starting current decreases, the weight of the lever will be sufficient to cause the hook to move into position to engage the next pin 48 on the gear which rotates the drum to hold the drum in a definite position. The slip coupling between the motor and the drum permits the motor to overrun without affecting the drum. If desired, the solenoid may be connected in a separate circuit to the control box to be controlled therefrom instead of from the motor circuit as above described.

It will be seen that the drum can only make one half of a revolution for each energization of the motor. If it is desired to alter the length of time required to change from one signal to another, as on highways where high speed requires a longer changing period, the gearing between the motor and the drum may be changed or the speed at which the motor operates may be altered.

Variations and modifications may be made within the scope of this invention and portions of the improvements may be used without others.

I claim:

1. In a signaling device comprising a housing having a stop and a go aperture, a plurality of light sources for illuminating each aperture; means mounted in the housing for varying in a predetermined manner the number of said light sources which are illuminated in each aperture during a change of the signal from stop to go to give a caution signal, said control means including a periodically driven rotary contact drum; a plurality of fixed contactors cooperating therewith to control the illumination of said light

sources; and electro-responsive means for arresting rotation of the drum to prevent overrunning thereof upon completion of a change of said signal from stop to go on one side and from go to stop on another side.

2. In a signaling device comprising a housing having a plurality of sides, each signaling side having a stop aperture and a go aperture, a plurality of light sources for illuminating each aperture; means for controlling said light sources in a predetermined manner throughout the period of changing of the signals, to give a caution signal which indicates the extent of lapse of said changing period, said control means including a rotary contact drum, fixed contactors cooperating therewith to control the illumination of said light sources in a predetermined manner, and electro-responsive means for rotating said drum during a change of the signal from stop to go, and for arresting rotation of said drum upon completion of such a change.

3. In a signaling device comprising a housing having a plurality of sides, each signaling side having a stop aperture and a go aperture, means for illuminating the apertures comprising a plurality of light sources for each aperture; means for controlling said light sources in a predetermined manner to give a caution signal including a rotary drum having stepped contacts thereon; fixed contactors cooperating therewith to control the circuits of said light sources as the drum rotates; a motor for rotating the drum, periodically operated to change said signal; and means for limiting the rotation of the drum upon completion of a change of said signal from stop to go for each operation of the motor.

4. A signaling device comprising a housing having a plurality of sides, each signaling side having a stop aperture and a go aperture; means for illuminating the apertures comprising a plurality of light sources for each aperture; control means for said light sources, including a rotary insulated drum having stepped contacts thereon, a plurality of fixed contactors cooperating therewith to vary the number of light sources which are illuminated in each aperture in a predetermined manner during a change of the signal; a motor operated at predetermined intervals for rotating the drum; and means for limiting the amount of rotation of the drum, including an electromagnetically operated latch for arresting rotation of the drum upon completion of a change of the signal from stop to go.

5. A signaling device comprising a housing with a plurality of sides, each signaling side having a stop aperture and a go aperture; means for illuminating the apertures comprising a plurality of light sources for each aperture; control means for said light sources including a rotary insulated drum having stepped contacts thereon; a plurality of fixed contactors cooperating therewith upon rotation of the drum to control the illumination of said light sources in a predetermined manner during a change of said signal; means for rotating the drum, including a periodically operated motor and a slip coupling interposed between said motor and said drum; and means for limiting the amount of rotation of the drum for each operation of the motor, including an electromagnetically operated latch which arrests rotation of the drum upon completion of the change of said signal from stop to go.

6. A signaling device comprising a housing with a plurality of sides, each signaling side having

a stop aperture and a go aperture; means for illuminating the aperture comprising a plurality of light sources for each aperture; control means for said light sources including a rotary insulated drum having stepped contacts thereon; a plurality of fixed contactors cooperating therewith upon rotation of the drum to control the illumination of said light sources in a predetermined manner during a change of said signal; a periodically operated motor, including a frictional driving means for rotating the drum; and means for limiting the amount of rotation of the drum, last-named means including a stop means associated with said drum, and an electromagnetically operated latch adapted to engage said stop means upon completion of each change of the signal from stop to go.

7. A signaling device comprising a housing and a plurality of sides, each signaling side having a stop aperture and a go aperture; means for illuminating the aperture, comprising a plurality of light sources for each aperture; control means for said light sources, including a rotary insulated drum having stepped contacts thereon; a plurality of fixed contactors cooperating therewith upon rotation of the drum to control the illumination of said light sources in a predetermined manner during the change of said signal; a periodically operated motor for rotating the drum to change the signal; a periodically energized circuit therefor; an electromagnetic means controlled by said circuit for arresting rotation of the drum upon completion of a change of said signal from stop to go during the period of rotation of the motor; and frictional driving means between the motor and said drum, whereby said motor may overrun after operation of the electromagnetic means.

8. A signaling device comprising a housing and a plurality of sides, each signaling side having a stop aperture and a go aperture; means for illuminating the apertures comprising a plurality of light sources for each aperture; control means for said light sources including a rotary insulated drum having stepped contacts thereon; a plurality of fixed contactors cooperating therewith upon rotation of the drum to control the illumination of said light sources in a predetermined manner during a change of said signal; means for arresting rotation of said drum upon completion of a change of said signal from stop to go; an intermittently operated motor for rotating said drum; a circuit therefor including an electro-magnetic means actuated by the initial surge of current through said circuit upon energization of the motor, for releasing said arresting means, and permitting rotation of the drum by the motor for changing the signal from stop to go.

9. An intersection traffic signal comprising a frame having a plurality of sides, each side having stop and go signals; means for illuminating the signals comprising a plurality of light sources to illuminate each signal, said means comprising at least two circuits, one of which includes the means for illuminating the stop signal for one traffic direction and the go signal for another traffic direction, and another circuit including the means for illuminating the go signal for the former and the stop signal for the latter traffic direction; means for controlling the illuminating means to indicate a change from stop to go, said means including a rotary contact drum having stepped contacts thereon; fixed contactors cooperating therewith upon rotation of the drum to

operate said circuits alternately, in each case first illuminating all the light sources in the circuit and then extinguishing said sources on both the stop and go sides as the drum rotates; a motor for rotating the drum operated during an interval for changing the signal; and means for arresting rotation of said drum to prevent overrunning thereof upon illumination of all of the light sources in either circuit.

10. A signaling device comprising a housing having a plurality of sides, each signaling side having a horizontal and vertical aperture, the horizontal aperture giving a stop signal and the vertical aperture giving a go signal; means for illuminating the signals, comprising a plurality of light sources to illuminate each of said apertures, said means comprising at least two circuits, one of which includes the means for illuminating the stop signal for one traffic direction and the go signal for another traffic direction, and the other circuit including means for illuminating the go signal for the former and the stop signal for the latter traffic direction; means for controlling the illuminating means to indicate a change from stop to go, said means including a rotary contact drum having stepped contacts thereon, fixed contactors cooperating with stepped contacts to operate said circuits alternately, in each case first illuminating all the light sources in the circuit and then extinguishing said sources in sequence on both the stop and go sides as the drum rotates; a motor for rotating the drum adapted to be operated during an interval for changing the signal; and means for arresting rotation of said drum to prevent overrunning thereof upon illumination of all of the light sources in either circuit.

11. In a signaling device comprising a housing having a stop and a go aperture, a plurality of light sources for illuminating each aperture; 40

means for controlling said light sources in a predetermined manner throughout the period of changing of the signal to give a caution signal which indicates the extent of lapse of said changing period, said controlling means including two relatively movable contact members, one of which carries stepped contacts and the other carrying a plurality of contacts cooperating therewith to control the circuits of said light sources in a predetermined manner upon relative motion of the contact members; driving means for effecting relative motion of said contact members, periodically operated for changing said signal; and electro-responsive means for limiting the relative motion of said members upon completion of a change of said signal from stop to go for each periodic operation of said driving means.

12. In a signaling device comprising a housing having a stop and a go aperture, a plurality of light sources for illuminating each aperture; means for controlling said light sources in a predetermined manner throughout the period of changing of the signal to give a caution signal which indicates the extent of lapse of said changing period, said controlling means including two relatively movable contact members, one of which carries stepped contacts and the other carrying a plurality of contacts cooperating therewith to control the circuits of said light sources in a predetermined manner upon relative motion of the contact members; electro-responsive driving means for effecting relative motion of said contact members, periodically operated to change said signal; and electro-responsive means for limiting the relative motion of said members upon completion of a change of said signal from stop to go for each periodic operation of said electro-responsive driving means.

THEODORE E. STEIBER.
